UNITED STATES PATENT OFFICE.

HARRY LATIMER, OF HIGH BRIDGE, NEW JERSEY.

ADJUSTABLE SHEET-METAL PIPE.

No. 818,267.

Specification of Letters Patent.

Patented April 17, 1906.

Application filed April 18, 1905. Serial No. 256,200.

To all whom it may concern:

Be it known that I, HARRY LATIMER, a citizen of the United States, and a resident of High Bridge, in the county of Hunterdon and State of New Jersey, have invented a new and Improved Adjustable Sheet-Metal Pipe, of which the following is a full, clear, and exact description.

In the erection of sheet-metal piping, such as stovepipes, considerable difficulty is experienced in forming the joints between the sections, as these joints should fit with nicety though the pipe-sections vary in dimension.

The object of this invention is to produce a form of pipe which is easily adjusted at its extremities to fit the adjacent sections.

Reference is to be had to the accompanying drawings, forming a part of this specification, in which similar characters of reference indicate corresponding parts in all the figures.

Figure 1 is an elevation showing a stovepipe constructed according to my invention. Fig. 2 is a perspective view showing the adjusting arrangement for the large end of the pipe-section. Fig. 3 is a developed plan showing a portion of one edge of the pipe at which the side seam is to be formed; and Fig. 4 is a view similar to Fig. 3, but representing the opposite edge in the act of being set into position to form the side seam.

Referring more particularly to the parts, 1 represents a stovepipe-section constructed according to my invention, the same being represented as connecting the pipe-sections 2 and 3. The pipe-section 1, when constructed according to my invention consists, substantially, of the usual cylindrical sleeve, the opposite longitudinal edges whereof meet to form a longitudinal seam 4. In order to form this seam 4, one of the longitudinal edges 5 is folded to form a crease 5^a and so as to present two plies, laps, or folds 6 and 7 at the edge, forming spaces between the same and between the pipe-body and the ply 7, as indicated. Into the space between the plies 6 and 7 the opposite longitudinal edge 8 of the sleeve is thrust, as indicated in Fig. 2.

In Fig. 3 the formation of the innermost ply 6 is fully illustrated. The edge of this ply is not plain in the manner usually found in stovepipes, but is serrated or scalloped, as indicated, so as to form a plurality of lobes 9, separated by recesses 10, which vary in depth progressively, as indicated by the dotted lines 11. Commencing near the small end of the stovepipe-section, they reach a minimum

depth at the point 12, beyond which point they become deeper again. In this way the entire length of the stovepipe-section is formed with a serrated edge, and the serrations are of a sufficient number so that the deepening of the recesses is repeated several times in the complete length of the pipe. Thus there is a succession of these rising-and-falling notches. From this arrangement if a pipe-section of standard length is cut to a shorter length this length may have its small extremity adjusted to form a joint in the same manner as the standard length. At the large extremity of the pipe the crease 5^a is cut away so as to form a recess or slot 5^b, as indicated most clearly in Fig. 2.

In forming the joint at the large end of the stovepipe-section 1 the edge 8 is simply thrust into the space between the plies 6 and 7, as suggested above, and is held in position there by means of a locking plate or clip 13. (Shown most clearly in Fig. 2.) This plate is riveted to the stovepipe-section at 14 and conforms to the curve of the pipe, as shown, extending in the direction of the seam 4. Its inner edge is provided with a plurality of recesses or notches 15, and these are adapted to engage the inner extremity of the slot 5^b between the edge 5 and the ply 7, in this way locking the edges of the seam together. In making the joint in this manner the longitudinal edges are brought together in a longitudinally-displaced position and then slid one upon the other until the plate 13 engages the extremity of the slot 5^b.

As any one of the notches 15 may engage the seam, the diameter of this end of the pipe may be adjusted to a larger or smaller dimension, as desired.

Arranging the edge of the lap 6 in a succession of progressively-deepening notches enables the diameter of the small extremity of the pipe-section 1 to be nicely adjusted. The manner in which the joint is formed at this point is clearly illustrated in Fig. 4. The edge 8 throughout its principal portion lies in the space under the lap 6, as illustrated in Fig. 2. At some notch, such as the notch 16, the edge 8 passes to the other side of the ply 6, passing through the notch 16, as will be readily understood. This arrangement brings about a certain diameter at the extremity 17 of the pipe-section. If this diameter were not found suitable for connection with the pipe-section 3, the notch 18 could be selected or the notch 19. The former notch would

give an increased diameter at the extremity of the pipe, while the latter would give a reduced diameter. Thus it will be seen that by selecting the proper notch a very accurate adjustment of the pipe-section may be made with respect to the pipe-section 3.

It should now clearly appear that with stovepipe-sections constructed according to this invention a stovepipe may be readily set up and the joints accurately made. This is an advantageous feature of the invention, as in present practice, although it is attempted to standardize pipes, they vary sufficiently to render it difficult to fit all sizes made or in the market. With stovepipe-sections constructed in this way the practice of nesting, which is resorted to so as to ship the pipes compactly, may still be used, as the longitudinal seam of the pipe-section is not permanently made until the pipe is set up.

Having thus described my invention, I claim as new and desire to secure by Letters Patent—

1. A pipe-section having longitudinal edges adapted to form a seam, one of said edges presenting a plurality of recesses of different depths, said recesses being adapted to receive the opposite edge to determine the diameter of the pipe-section.

2. A pipe-section consisting of a sleeve having longitudinal edges adapted to come together to form a lapped seam, one of said edges having a succession of recesses of progressively-increasing depth, said recesses being adapted to receive an opposite edge and determining the diameter of said pipe-section.

3. A pipe-section consisting of a sleeve having longitudinal edges adapted to overlap to form a seam, one of said edges being folded

so as to form an inner ply and a groove adjacent thereto, said groove being adapted to receive the opposite edge, said inner ply having a serrated edge presenting a plurality of recesses of progressively increasing and decreasing depth, said recesses being adapted to receive the said opposite edge of said sleeve near the extremity of said pipe-section to determine the diameter thereof.

4. A stovepipe - section consisting of a sleeve having extremities of different diameters, the small extremity of said sleeve having notches in a longitudinal edge thereof, said notches progressively increasing in depth and being adapted to receive the opposite longitudinal edge to determine the diameter of the small extremity of said pipe-section, and means for adjustably locking the said edges at the other extremity of said pipe-section.

5. A stovepipe-sleeve having a longitudinal edge thereof folded to form a crease and a groove adjacent to said crease, said groove being adapted to receive the opposite longitudinal edge and said crease having a slot formed therein at the extremity of said sleeve, and a locking-plate rigidly attached at said opposite edge and received in said slot, said locking-plate having a plurality of notches in the edge thereof adapted to engage the end of said slot, and affording means for adjusting the diameter of said sleeve.

In testimony whereof I have signed my name to this specification in the presence of two subscribing witnesses.

HARRY LATIMER.
